UNITED STATES PATENT OFFICE.

DUNCAN D. McBEAN, OF NEW YORK, N. Y.

TUNNEL CONSTRUCTION.

1,163,096.

Specification of Letters Patent.

Patented Dec. 7, 1915.

Original application filed May 27, 1914, Serial No. 841,228. Divided and this application filed November 5, 1914. Serial No. 870,377.

To all whom it may concern:

Be it known that I, DUNCAN D. McBEAN, a citizen of the United States, residing at New York, in the county and State of New York, have invented certain new and useful Improvements in Tunnel Construction, of which the following is a full, clear, and exact description.

This application is a division of an application filed by me on May 27, 1914, Serial No. 841,228.

The invention subject of the application is an improvement in apparatus for unwatering and excavating material below water level in the installation and construction of structures, such as tunnels and sewers, that are built above or on the water level, or the surface of the material to be excavated, and for lowering the same into place step by step as the material beneath them is removed.

The improvements are also applicable to the excavation below water level of material for the erection of such structures as dry docks, and for the deepening of river and channel bottoms, but in the present application the invention disclosed and claimed is concerned only with and will be described as applied to the construction and installation of tunnels and sewers.

The invention described and claimed herein involves novel means whereby in excavating through water bearing material, either on shore or in river or channel bottoms, the hydrostatic pressure on the outside of the sheeting which I place upon the banks on the sides of the excavation, is neutralized or equalized by the provision of the same hydrostatic pressure against the inside of the sheeting above the bottom level of the structure that is being lowered, and whereby there will be provided on the inside of the sheeting which is below the level of the bottom of the structure, a body of air under sufficient pressure to equal hydrostatic pressure that exists against the outside of that part of the sheeting, thereby preventing the water, quicksand and other flowing materials from entering the excavated space from under the sheeting, and thereby reducing the pressure on the outside of the sheeting to that due to the difference between the weight of earth and that of the water.

My invention further resides in novel appliances whereby structures, such as lengths

of tunnel or sewer built at the surface of the water, may be expeditiously and economically lowered into place through water bearing material on shore or in river bottom, and lessen the friction between it and the banks, while it is being lowered, although the structure is used as a support for the banks.

Finally, my invention involves such means as shall provide for the floating of the structure after it has been sunk to the required depth, whereby it is free to be moved into the exact grade and alinement required.

In the accompanying drawings, I have illustrated my improved construction, and by reference to the same I shall describe the methods or processes which I follow in using the same for its intended purpose.

Figure 1 is a vertical transverse cross-section of a double tube tunnel construction and the appliances used in connection therewith, in the process of lowering it to the desired level. Fig. 2 is a similar section, showing the conditions and relations of the tunnel and its appurtenances after a certain amount of excavation has been accomplished. Fig. 3 is a horizontal sectional plan showing the arrangement of sheeting surrounding the structure and the intermediate devices employed therewith. Fig. 4 is an enlarged sectional detail of the section of Fig. 1. Fig. 5 is a detail view of the sheeting showing the means of joining sections of the same. Fig. 6 is a cross-section showing a completed section before all of the sheeting and supports are removed.

Similar numerals of reference indicate corresponding parts in all the figures.

The tunnel structure may consist of one or more tubes and may be built at any convenient point in the desired lengths, which may be two hundred feet or more, and floated or carried to the point where it is to be sunk in place. It is composed of iron or steel uprights 1 and transverse roof and floor beams 2, 3, all secured together to form a skeleton frame. To the outside of each of the steel uprights 1 on the exterior of the structure, there is bolted a vertical plank to which horizontal tongued and grooved water tight planks 4 are pinned with maple pins, thus forming a water proofing which incloses the sides of the skeleton frame. The spaces between the steel uprights and the transverse roof beams, are filled solid with concrete 5.

The water-proofing planking is placed on the top of the roof beams and intermediate concrete and joined to the water proofing on the sides, and an outer covering of concrete 6 is laid over the water proof planking on the top, to protect it from the attack of marine insects in case it should be exposed directly to the water.

Extending completely through the structure is an air lock shaft 8, and extending only into the structure is a second air-lock shaft 9, for the purposes which will herein-after appear. Through stuffing boxes in the temporary floor 4, there extend cylindrical steel piles 10, and the pipes of a sand or mud pump 11. Otherwise, each section of tunnel is inclosed on all sides, the ends being closed by temporary bulk-heads 12, in order to make the structure water-tight.

The method of installing a single section of tunnel thus constructed is as follows: I-beams or columns 13 of a length sufficient to extend from the top to near the bottom of the structure, are secured vertically at intervals along the sides and ends of the same and secured in position to the planking of the structure.

A second set of very much heavier I-beams or columns 14, of a length sufficient to extend from near the level of the bottom of the structure to about one foot above its roof or top, is placed vertically outside of and opposite to the inner beams 13, with a space of a few inches between the two which is maintained by wedges 15 and braces 34, placed between them at intervals of a few feet of their height. These outside beams 14 are held in place by bolts 16, passing through the outer flanges of the inner and the inner flanges of the outer beams. A pair of vertical beams on one side of the structure are placed opposite a pair on the other side, and the tops and bottoms of the outer beams are united by braces 17, extending across between them above the top and beneath the bottom of the structure. The lower sides of beams 14 are secured by flanges 22 and bolts 23 to a heavy planking 24, as shown in detail in Fig. 4, and the space between this planking and the base of timber 25, to which the lower ends of beams 13 are similarly secured, as shown in the same figure, is closed with I-beams 26.

Consecutive tiers, one above the other and a few feet apart, of horizontal walings or ranges 18, are placed continuously along the sides and across the ends of the structure, and a few inches outside of the vertical beams 14, to which they are temporarily attached, as by bolts or otherwise. The lower tier of walings 18, is placed so as to be on a level with the heavy planking 24.

Between the tiers of walings 18, there are placed at intervals vertical braces 19, the tie-rods 20, and fixed rollers 21 are secured

to the inner upright faces of the walings opposite to and contiguous with the outer flanges of the vertical beams 14, and the few inches of space between the bottom of the lower tier of horizontal walings and the bottom of the horizontal planking 24, to which the beams 14 are secured, are closed by planks 26 placed under them and overlapping them both.

Vertical planks of sheeting 27, the length of which is substantially equal to the depth of excavation required, are placed close together on the outside of the tiers of horizontal walings 18, to which they are temporarily attached. In order to secure a good and water tight joint between the sections of this sheeting, I have adopted the form of joint shown in Fig. 5, in which 43 is an iron or steel plate set in the edge of one section of sheeting and 44 are similar plates extending over a recess and secured to the edge of the opposite section to form a socket in which a projection on the plate 43 may enter and slide when the two sections are associated. To support the sheeting and guide it while being driven, there are placed on the outer side tiers of horizontal walings 28, which are temporarily held in place by bolts passing through them, through the sheeting and the inner walings 18. The insertion of the sheeting 27 may be postponed until after the structure is floated, the space therefor between the outer and inner tiers of walings being maintained by blocking inserted at intervals between the two.

The structure and its appurtenances as thus assembled is launched or floated, generally by sinking the float on which the parts described are assembled, and towed to a point immediately over its intended site. A few piles 32 are then driven down through stuffing boxes, provided for them in the planking 24, for several feet into the material to be excavated, and collars 33, as shown at the left in Fig. 1, are secured to them by divers at the elevation to which it is intended to at first lower the structure.

The buoyancy of the structure is overcome either by introducing into it loosely on its temporary flooring 4 a portion of the material that will be subsequently utilized to fill in the spaces between the floor beams, or by permitting sufficient water to enter the same, or by adding weight, in control of derricks, onto the structure sufficient to sink it. Blocking 30 is placed at intervals in the material to be excavated upon which the bottom plank 26 rests, and the structure is in this way supported on the bottom. After the structure is alined as nearly as possible, the piles 10 are driven for a few feet into the material under the same, and collars 29 are then adjusted by divers on such piles in contact with the flooring 4, so that the entire structure will be supported at proper

levels in its correct position. When the tunnel section has been thus adjusted and alined, the sheeting 27 is detached from its temporary union with the walings and driven entirely around the structure for a few feet into the material to be excavated. Simultaneously, air is pumped under the floor of the structure, which, as will be seen from the above description, forms a substantially air-tight compartment, and sufficient water is permitted to enter the structure itself to give it sufficient weight to withstand the pressure of air which it is necessary to have under the flooring. Workmen then descend from the surface, through the air lock shaft 8, which passes through stuffing boxes in the top and bottom of the structure, and excavate the material under the flooring. This is accomplished either by introducing water, as through a pipe 31, and pumping out the sand and mud therewith by the pump within the tunnel section, or by hoisting out the material in buckets through the air lock shaft 8. The material is thus excavated for a depth of several feet when walings 18, as shown in Fig. 2, carried down into or previously stored in the compartment under the floor, are placed against the sheeting 27. They may be temporarily held in position by braces between them and the piles 32, and on their inner faces are fixed rollers corresponding to those above described. When the excavation in this way has been completed, the collars on the piles 10 and 32 are lowered to the level of the bottom walings and water is admitted thereto through the pipes 31 or by the removal of planks 26. For this purpose the air pressure under the floor is reduced, while that in the structure is increased. The structure is caused to slowly slide down between the fixed rollers 21 on the walings, and the vertical beams 14, until it rests upon the blocking or planking and collars prepared for its reception, and a water tight compartment again formed by the stoppage of the space between the walings and the planking. The water in this compartment under the floor is then forced up into the tunnel by decreasing the air pressure in the latter and increasing that under the floor. These operations of excavating and lowering the structure are repeated until the excavated recess is of the required depth at which the structure is to permanently rest. If at such a time it is found not to be in true alinement, the piles 10 and 32 are withdrawn or cut, or burned off and the I-beams 13 and wedges removed, whereupon the structure will be virtually afloat in the space between the vertical beams 14 and the cross beams 17. By the adjustment of the wedges 15, or otherwise, the structure is then forced into exact alinement with a section previously in place. When this has been done,

air is pumped into the structure until the hydrostatic pressure is equal to the hydrostatic pressure at the level of the temporary floor 4. This floor is then removed and the pressure increased within the structure until it equals the hydrostatic pressure at the level of its foundation, which is then prepared, a new water-tight flooring 35, laid on the cross-beams 17, and the spaces above the floor and between the horizontal beams filled in with concrete and the structure completed. The horizontal planking 24 is then detached by divers from the beams 14, the sheeting 27 drawn and all of the appliances utilized in the construction and installation of the tunnel removed or allowed to float up. After each section of tunnel is completed, the air lock shafts 8 and 9 are removed.

The above is the complete method of installing a single section of tunnel and no other steps are necessary when the entire structure consists of but a single section. In case, however, that the finished structure is made up of two or more such sections, special provision must be made for connecting them together into an integral whole. I have shown and described the means for doing this in my application Serial No. 841,228, filed May 27, 1914.

When a tunnel or sewer is to be constructed on shore, and where the material to be excavated is water bearing, the procedure above described will be modified somewhat to meet the change of conditions involved. In such cases the structure and its appurtenances above set forth, are assembled above the surface of the water in the ground to be excavated, and the space below the water level between the driven sheeting 27 and the structure, as well as that over the latter, as it is lowered into the ground, is kept filled with water up to the level of the water in the ground outside of the sheeting, but as this supply of water must not be permitted to flow in under the sheeting it may have to be brought from an outside source. When the depth of the excavation below the level of the outside water is greater than the height of the structure, through bracing between the walings on the opposite sides must be introduced over the structure, but otherwise the procedure is the same as that for subaqueous tunnels described above.

The invention herein set forth constitutes a radical departure from the established practice and presents many advantages which no other system possesses. In the building of subaqueous tunnels, it permits the excavation, whatever the material, to be effected at a much less cost than it can be done in any other way. The quantity of material to be removed is reduced to a minimum, and if it be soft, it may be pumped out instead of being dug and hoisted to the

surface. The possibility of placing the pumps in the water tight compartment or sections of the structure at a depth perhaps many feet below the surface of the water, 5 increases their efficiency many fold, because of the hydrostatic pressure due to the depth operating to force material into the pumps, whereby there will be a much larger percentage of material carried along with the 10 water through the pump than if the latter had only the vacuum which it creates itself. In cases where rock is encountered, it may be unwatered and blasted and then excavated 15 at a much lower cost than by the ordinary methods.

In the building of tunnels or sewers in streets between buildings, the foundations of 20 which rest on sand or water bearing material, the tunnel structure may be carried to a level well below that of the foundations without disturbing either the sand or the water in the material outside of the sheeting which retains the banks of the excavation. It makes cut and cover work an absolutely 25 safe and sure method of making an excavation to any depth under one hundred feet.

What I claim is:

1. As an improvement in subaqueous tunnel construction, the combination with a 30 tunnel or section thereof, of vertical beams attached thereto, sheeting surrounding the same and supporting the banks of the excavation, and guide rolls between the supporting walings of such sheeting and the 35 vertical beams.

2. As an improvement in subaqueous tun-

nel construction, the combination with a section of said tunnel, of vertical beams attached to the sides and ends thereof, sheeting surrounding the section and supporting the 40 banks of the excavation, guide rolls between the walings of the sheeting and the said beams, and a water tight partition between said sheeting and the structure at the bottom of the tunnel section. 45

3. As an improvement in subaqueous tunnel construction, the combination with a section of said tunnel, of sheeting surrounding the section and supporting the banks of the excavation, means for adjusting the position of the section within the sheeting and permitting it to be lowered therein, and a water tight partition placed between the sheeting and the structure at the bottom of the section. 50

4. As an improvement in subaqueous tunnel construction, the combination with a section of said tunnel, of sheeting surrounding the section and supporting the banks of the excavation in which it is contained, and 60 means within the walls of water between the sheeting and the tunnel section for guiding the tunnel section and floating it at any level in the body of water contained within the sheeting, as set forth. 65

In testimony whereof I affix my signature in the presence of two subscribing witnesses.

DUNCAN D. McBEAN.
